[57] **CLAIM**

The ornamental design for a window cover, as shown and described.

DESCRIPTION

FIG. 1 is a front elevational view of a window cover, showing a typical embodiment of my new design. The rear elevational view is identical;

FIG. 2 is a left vertical side view of the window cover of FIG. 1. The right side view is the same; and,

FIG. 3 is a top plan view of the window cover of FIG. 1. The bottom plan view is identical.
